(57) **CLAIM**

The ornamental design for a combined lighter and extinguisher for aerosol generator, as shown and described.

DESCRIPTION

FIG. 1 is a front, top, and left side perspective view of a first embodiment of the combined lighter and extinguisher for aerosol generator showing the new design in a symbolic break line.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a front, top, and left side perspective view of a second embodiment of the combined lighter and extinguisher for aerosol generator showing the new design in a closed configuration.

FIG. 9 is a front elevational view thereof.

FIG. 10 is a rear elevational view thereof.

FIG. 11 is a left side elevational view thereof.

FIG. 12 is a right side elevational view thereof.

FIG. 13 is a top plan view thereof.

FIG. 14 is a bottom plan view thereof.

FIG. 15 is a front, top, and left side perspective view showing the combined lighter and extinguisher for aerosol generator in an open configuration.

FIG. 16 is a front, top, and left side perspective view of a third embodiment of the combined lighter and extinguisher for aerosol generator showing the new design in an open configuration.

FIG. 17 is a front elevational view thereof.

FIG. 18 is a rear elevational view thereof.

FIG. 19 is a left side elevational view thereof.

(Continued)

FIG. 20 is a right side elevational view thereof.

FIG. 21 is a top plan view thereof.

FIG. 22 is a bottom plan view thereof; and,

FIG. 23 is a front, top, and left side perspective view showing the combined lighter and extinguisher for aerosol generator in a closed configuration.

The combined lighter and extinguisher for aerosol generator is shown with a symbolic break in its length. The appearance of any portion of the article between the break lines forms no part of the claimed design.
